UNITED STATES PATENT OFFICE.

ALBERT STEFFIN, OF NEW BEDFORD, MASSACHUSETTS, ASSIGNOR TO THE MOUNT WASHINGTON GLASS COMPANY, OF SAME PLACE.

DESIGN FOR A VESSEL.

SPECIFICATION forming part of Design No. 22,367, dated April 25, 1893.

Application filed January 11, 1893. Serial No. 458,094. Term of patent 7 years.

To all whom it may concern:

Be it known that I, ALBERT STEFFIN, of New Bedford, in the county of Bristol and State of Massachusetts, have invented a certain new and original Design for a Vessel, &c.; and I do hereby declare the following specification, taken in connection with the accompanying drawing, forming a part of the same, to be a full, clear, and exact description thereof.

The characteristic feature of my design consists of a vessel formed to represent a flower, such as a pansy, supported upon a base formed to represent one or more leaves of the same flower.

Referring to the drawing, A represents the vessel proper, and B the base or support therefor. The portion A is formed to represent a pansy resting upon the base B, which is formed to represent a series of leaves b.

What I claim as my invention, and desire to secure by Letters Patent, is—

The design for a vessel substantially as herein shown and described.

ALBERT STEFFIN.
